(57) **CLAIM**

The ornamental design for a combined container and bottle, as shown and described.

DESCRIPTION

FIG. 1 is a perspective view of a combined container and bottle showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a container wherein a front endcap is pulled from the container to reveal the cap of the bottle;

FIG. 9 is a perspective view, showing the container and bottle in an alternate, deployed state where the bottle is removed from the container and the cap removed from the bottle to reveal the two covers;

FIG. 10 is a front perspective view thereof;

FIG. 11 is right-side view thereof;

FIG. 12 is a rear perspective view thereof;

FIG. 13 is a right-side view thereof, showing the plane upon which a cross section is taken and shown in FIG. 14; and, FIG. 14 is a cross sectional view thereof taken along line A-A in FIG. 13.

The broken line showing of a harness, the interior surfaces of the container, and the interior surfaces of the bottle is included for the purpose of illustrating environmental structures and forms no part of the claimed design.
